SAID NOVICK ASSIGNOR TO SAID YOUNG

AUTOMATIC CLOSURE FOR PORTABLE RECEPTACLES

Application filed February 28, 1927. Serial No. 171,578.

This invention relates to means for sealing a portable reservoir such as an oil barrel and to automatically operated means to permanently seal said receptacle from the reinsertion of a withdrawal pump when the pump has been removed therefrom.

In the commercial world dealing with the sale of large quantities of fluids such as for example the sale of lubricating oil in drums, it has been the practice of the producing companies to characterize their containers with appropriate advertising marks in order that the purchaser was fully aware of the product that he was buying and also that the dealer would be able to guarantee to the consumer that the oil from that certain drum was as advertised.

It is the practice of some of these companies however, to discard and not refill the drums after they have once been used. This has been necessary as an economical measure because the expense of reshipping the drum to a distribution point to be cleaned, reshaped, repainted and refilled would involve more than the cost of manufacturing new drums. Consequently, with no return of the old drum, they have accumulated among the retail dealers who, with questionable integrity, have too frequently refilled them with any variety of oil that was offered and then reinserted the pump to continue dispensing the bogus oil. It can be readily understood that an empty oil drum with some well known producing company's name thereon, is a highly desirable medium to transport oil and if an inferior grade at a much lower price can be purchased for sale to an unsuspecting public as a better grade at a standard price, the unscrupulous agent is the beneficiary to the loss of the public who gets an inferior oil and to the loss of the producing company, who loses the public's "goodwill", a highly valuable asset, and furthermore loses the profit on the sale of its own oil.

However, if a means is provided to prevent a reinsertion of the pump, even though the receptacle may be refilled, the refilled receptacle is obviously of no material use for the attendant difficulty attached to removing a

quantity of oil for example, without a pump, is considerable.

It is therefore the principal object of our invention to provide a relatively inexpensive automatically operated sealing device which is to be incorporated into such a receptacle so that after the material is withdrawn and the pump removed, no pump can be reinserted.

It is a further object of this invention to provide a sealing means for portable receptacles which will be operated by the removal of the withdrawal pump from the receptacle.

It is a further object of this invention to provide an inexpensive bung seal for a portable receptacle to render it impossible to reinsert a pump after the first insertion.

Other advantages and objects of the invention will appear as the description of the following drawings proceeds and, in which,

Figure 1 is a vertical section through our improved bung seal.

Figure 2 is a plan view of the seal shown in Figure 1.

Figure 3 is a sectional view on the line 3—3 of Figure 2 showing the details of the slide valve.

The portable receptacle partially shown as a metallic drum 1 is adapted to have the improved automatic bung seal 2, integrally attached to it, on the inside as by welding 80 and is provided with the bung opening 3 corresponding with the screw threaded portion 4 of the bung seal 2, into which the pump (not shown) is mounted. The bung seal also has a reduced portion 5 that guides 85 the stem of a suction pump 20, and a shoulder 6 serving to retain the metallic cup 7 temporarily in position.

Integral with the side and bottom of the sealing means 2 is a rectangular flange 8 with inturned lips 9 forming a grooved track for the movable slide 10 which is resiliently forced to the closure position by means of a spring 11, snapped over the end of the plate 10 and attached to a vertical outwardly projecting boss 12 on the side of the bung seal 2. Any convenient attachment may be made although a pivot with the retaining cotter key is shown for purposes of illustration.

Within the boss 12, is a cylindrical bore 100

provided with a movable pin 14 urged downward against the slidable plate 10 by means of a resilient spring 15.

The operation of the device is as follows: 5 If the cup 7 is forced out of retaining engagement with the plate 10 by the coaction of the stem of the pump 20, the plate, under resilient pressure of the spring 11, will be forced into closure position as shown in dotted lines in Figure 1. Then, the plate portion in contact with the lower end of pin 14 being removed, the pin 14 is forced downward by the spring 15 until it contacts with a depressed portion of the plate 10 and abuts 10 the vertical portion 10a and thus securely 15 holds the plate in a closure position from which the plate can not be removed.

It is the intent of this invention to contemplate the use of the pump 20 to remove the 20 contents of the drum and which pump will be provided with an intake pipe extending into the liquid to be removed, and which pipe will immediately remove the cup 7 from its position of retaining the slidable plate 10 25 to some other position in the receptacle. The pump intake pipe then occupies the entire space of the opening and it in turn prevents the slide from shifting. However, as soon as the fluid is removed and the pump with- 30 drawn from the receptacle, no contact is had with the edge of the plate 10 and it is immediately forced shut and simultaneously locked.

The downwardly bent flange portion of 35 the slide 10 allows removal of a pump whose intake pipe will act on the bent portion to force the slide to the right as shown in Figure 1 to allow withdrawal without interference.

40 It will thus be seen that we have provided a simple, effective, inexpensive lock for a bung seal that will automatically operate under the certain conditions described and which will be impossible to reopen to allow 45 reinsertion of a pump or other withdrawal means. It is, of such nature that it may be integrally attached to the interior of the drum during its construction and when the drum is discarded, no great loss will occur.

50 However, it is our intention to illustrate one form of embodiment of this invention, and we have therefore shown one form which is illustrative rather than restrictive and we do not wish to be limited except as in the 55 scope of the appended claims.

We claim:

1. In a portable receptacle having a bung opening and adapted to be emptied by a withdrawal means inserted therethrough, an 60 automatic sealing and locking means closing said opening upon removal of the withdrawal means to prevent reinsertion of the withdrawal means.

65 2. In a portable receptacle of the class described, an automatic non-refilling means

comprising an integral cylindrical bung seal, a slide valve in said seal, and a means to keep the valve open before the fluid is withdrawn.

3. In a portable receptacle of the class de- 70 scribed, a cylindrical screw threaded bung seal non-removably attached adjacent the bung of the receptacle, a resiliently actuated slide valve and a resiliently operated lock pin for permanently locking the valve closed. 75

4. In a portable receptacle of the class de- 80 scribed, a bung seal integral with the recep- tacle, an automatic slide valve sealing said bung, and means to prevent reopening of the seal.

5. In a portable receptacle having a bung opening and adapted to be emptied by withdrawal means inserted through said opening, the combination of an automatic bung sealing means attached to the receptacle, comprising a closure means operated after the 85 contents of the receptacle are removed, and a lock means to prevent reinsertion of the fluid withdrawal means in the receptacle.

6. In a portable receptacle of the class de- 90 scribed, a cylindrical bung seal integral with said receptacle, an automatically operated closure means on the base of said seal, a cup shaped retainer normally preventing operation of said closure means, and allowing 95 actuation of said closure means after fluid has been removed from said receptacle.

7. In a portable receptacle having a bung opening and adapted to be emptied by withdrawal means inserted through said opening, the combination of an automatic, integral 100 bung seal on said receptacle, comprising a cylindrical portion, a cup shaped retainer in said portion, a slide valve resiliently actuated to closure position, the retainer prevent- 105 ing closure, and being removed from retaining position by the insertion of the withdrawal means, said slide valve closing after removal of the withdrawal means.

8. In a portable receptacle having a bung opening and adapted to be emptied by withdrawal means inserted through said opening, the combination of an integral bung seal comprising a cylindrical portion, a slide valve resiliently actuated to seal said cylindrical portion, said slide valve being provided with a downwardly projecting lip to allow un- hindered removal of the withdrawal means, a cup shaped retainer in said cylindrical portion normally preventing closure of the seal- 110 ing valve and adapted to be removed upon insertion of the withdrawal means, the slide valve permanently sealing the receptacle upon removal of the fluid withdrawal means. 115

9. In a portable receptacle having a bung opening and adapted to be emptied by a withdrawal means inserted therethrough, an automatic sealing and locking means adapted to hold said bung opening open until an au- 120 thorized withdrawal means is inserted and 125

adapted to prevent the reinsertion of any withdrawal means after the receptacle has been drained and the authorized withdrawal means removed therefrom.

5 10. In a portable receptacle having a bung opening and adapted to be emptied by withdrawal means inserted through said opening, the combination of an automatic sealing means comprising an integral seal, a slide

10 valve in said seal, means to keep the valve open before the fluid is withdrawn, said valve automatically closing after the fluid has been withdrawn to prevent reinsertion of the withdrawal means.

15 11. In a portable receptacle of the class described, a bung seal non-removably attached adjacent the bung of the receptacle, a resiliently actuated slide valve therein, means to keep said slide valve open before

20 the fluid is withdrawn and lock means for permanently locking the valve closed after the slide valve retaining means has been displaced.

25 12. In a portable receptacle of the class described, a bung seal integral with the receptacle, an automatic slide valve sealing said bung, a cup-shaped retaining means to prevent said slide valve from closing and means to prevent reopening of the seal when said retaining means has been displaced.

30 13. In a portable receptacle having a bung opening and adapted to be emptied by withdrawal means inserted through said opening, the combination of an automatic bung sealing means integrally attached to the receptacle comprising a closure means operative after the withdrawal means of the receptacle are removed and a locking means to prevent reinsertion of any fluid withdrawal means through the sealed bung in the receptacle.

35 14. In a portable receptacle having a bung opening and adapted to be emptied by withdrawal means inserted through said opening, the combination of an automatic integral bung seal on said receptacle comprising a cylindrical portion, a cup-shaped retainer in said portion, a slide valve resiliently actuated to closure position, said retainer preventing closure and being removed from retaining position by the insertion of the authorized withdrawal means, said slide valve closing after removal of the withdrawal means and preventing reinsertion thereof.

40 15. In a receptacle of the class described, an automatic non-refilling means comprising an integral bung seal, a sleeve in said sealing means to normally hold said valve open, said retaining means adapted to be displaced upon the insertion of a withdrawal means and means to positively lock said valve closed when the withdrawal means is removed.

45 16. In a receptacle of the class described, having a bung opening and adapted to be emptied by a withdrawal means inserted thru said opening, an automatic sealing means

comprising an integral seal, a sleeve in said sealing means to hold said valve normally open, said means adapted to be rendered ineffective when the withdrawal means is inserted thru said bung, and means to automatically close and lock said valve after the withdrawal means has been withdrawn to prevent the reinsertion of any withdrawal means.

50 17. In a receptacle having a bung opening, adapted to receive a withdrawal means thru said opening, the combination of an integral bung seal, sleeve means to retain said valve open, said retaining means adapted to be removed from retaining position by the insertion of withdrawal means, said valve closing after the removal of the withdrawal means.

55 In testimony whereof we have affixed our signatures to this specification.
